UNITED STATES PATENT OFFICE

2,576,626

WINDOW

William C. Miller, Plant City, Fla.

Application May 20, 1949, Serial No. 94,275

2 Claims. (Cl. 20—62)

1

The present invention relates to new and useful improvements in windows and more particularly to a window constructed of pivoted louvers.

An important object of the invention is to provide a window constructed of glass louvers with a novel bracket construction for pivotally mounting the ends of the louvers in a window opening whereby the window may be mounted in window openings of various sizes merely by cutting the glass louvers to a proper length.

It is a common practice in building constructions to place a standard window frame in a desired position and fill in the wall at the sides of the frame with broken bits or fragments of the brick or cement blocks at the window openings with the window frame placed in a wall in a position where entire bricks or blocks cannot be used at the window opening, and it is accordingly an object of the present invention to provide a window construction which eliminates the use of the conventional window frame and whereby the window may be placed in a window opening to the best advantage without the customary waste of labor and material in forming the window opening to a particular size window frame.

A further object of the invention is to provide a louver type window of simple and practical construction, which is neat and attractive in appearance, relatively inexpensive to manufacture and install in position and which otherwise is well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the outside of the window;

Figure 2 is an enlarged fragmentary perspective view showing the bracket construction for the glass louvers at one side of the window;

Figure 3 is a fragmentary vertical sectional view showing the louvers in closed position;

Figure 4 is an enlarged transverse sectional view taken on a line 4—4 of Figure 3;

Figure 5 is a group perspective view of the pair of angle iron members forming a bracket for each end of the louver;

Figure 6 is an enlarged fragmentary sectional view taken on a line 6—6 of Figure 4;

Figure 7 is an enlarged fragmentary perspective view of a sealing strip for the meeting edges of the louvers.

2

Referring now to the drawings in detail wherein for the purpose of illustration, I have disclosed a preferred embodiment of the invention, the numerals 5 and 6 designate channeled metal jambs positioned vertically in a window opening 7 and each provided at their outer edges with a flange 8 riveted or otherwise suitably secured in overlapping relation to a vertical jamb plate or block 9 embedded in the window opening. The channel of the jambs 5 and 6 face toward the outside of the window. An angle iron jamb weather strip 10 is welded or otherwise suitably secured in a vertical position in each of the channels 5 and 6.

A plurality of louver supporting brackets designated generally at 11 is constructed of a pair of angle irons 12 and 13 and welded or otherwise suitably secured to each other in a position with the flange 14 of the member 12 in confronting relation against the inner surface of flange 15 of member 13 and with the other flange 16 of member 12 spaced from the other flange 17 of member 13 to receive the end of a glass panel or louver 18 therebetween. The confronting flanges 14 and 15 of the brackets are pivoted at their central portions to one of the channeled jambs 5 and 6 by rivets or the like 19.

The ends of the bracket members 12 and 13 overlap to project one end 20 of the member 12 outwardly beyond the adjacent end of the member 13 and to project the end 21 of member 13 outwardly beyond the adjacent end of member 12. The outwardly projecting end of flange 16 of member 12 is formed with an angular lug or tongue 22 and the outwardly projecting end 21 of member 13 is similarly formed with an angular lug or tongue 23 opposed to lug 22 and between which the longitudinal edges of louver 18 are positioned to hold the louver in the brackets.

The flange 14 of bracket member 12 at its outwardly projecting end 20 is formed with an apertured ear 24 pivoted in a channel 25 of an outer vertical louver connecting bar 26 by means of a rivet or the like 27, and the flange 15 of bracket member 13 at its outwardly projecting end 21 is formed with an apertured ear 28 pivoted in a channel 29 of an inner vertical louver connecting bar 30 by means of a rivet or the like 31. The inner connecting bar 30 is also the operating bar for the louvers.

The brackets 11 at each end of the louvers 18 are similarly pivoted to inner and outer vertical louver connecting bars which are positioned at the free edge of the channeled jambs 5 and 6 and the outer connecting bars 26 are formed with inwardly projecting flanges 32 which move

into a confronting position against the outer surface of the outwardly projecting flange 33 of angle iron weatherstrip 18 when the louvers are closed, as shown in Figure 4.

A weather sealing channel member 34 similar in cross section to outer connecting bar 26 is constructed of upper and lower sections 35 and 36 slidably connected to each other, the upper end of upper section 35 being pivoted in an inverted position to a lug 37 welded to the upper end of each jamb 5 and 6 and with the lower end of lower section 36 pivoted to the upper end of channel 25 of outer connecting bar 26 by means of uppermost rivet 27 to receive the flanges 14 and 15 of uppermost bracket 11 in channel 34 when the louvers are closed and to seal the upper end of jambs 5 and 6. The edge of flange 15 of uppermost bracket member 13 at its end 21 is notched as shown at 39 to receive lug 37 when the window is closed.

A projection 40 is formed on end 20 of bracket member 12 to enter the channel of member 34 and hold the same close to one side of channel 25 so that uppermost bracket 11 may enter channel member 34 without interference.

The louvers 18 may be constructed of suitable width to overlap when closed, as shown in Figure 3 or the louvers may be cut of proper width to lie in a vertical plane, when closed, as shown in Figure 7 and are then provided at their meeting edges with a suitable sealing strip 41.

In the operation of the device, channel jamb members 5 and 6 are secured in the sides of a window opening and brackets 11 pivoted thereto with glass louvers 18 cut to a proper length and held at their ends in the brackets by bending the tongues 22 and 23 against the opposite side edges of the louvers. The ends of the brackets are pivoted in the channels of the inner and outer connecting bars 30 and 26 which move vertically into and out of close fitting engagement against the inner and outer sides of jambs 5 and 6 by the opening and closing of the louvers, said connecting bars 30, 26 forming weather strips when the louvers are closed.

In view of the foregoing description taken in conjunction with the accompanying drawings it is believed that a clear understanding of the device will be quite apparent to those skilled in

this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A window including louvers and comprising a pair of channeled jambs secured in the sides of a window opening, brackets pivoted to the sides of the jambs and including double flanges between which the ends of the louvers are positioned, oppositely extending tongues on opposite ends of the flanges positioned against the side edges of the louvers to hold the louvers in the brackets, inner and outer channeled vertical connecting bars in which the ends of the brackets are pivoted, the channels of the outer connecting bars being opposed to the channels of the jambs for interfitting sealing engagement with each other when the louvers are closed, and a channeled sealing member pivoted at its ends to the upper ends of the jambs and to an adjacent outer connecting bar and movable into interfitting engagement with the uppermost bracket and with the outer connecting bar when the louvers are closed.
2. The combination of claim 1 wherein said sealing member is composed of upper and lower channel sections slidably connected to each other.

35 WILLIAM C. MILLER.
